UNITED STATES PATENT OFFICE.

LEWIS C. MALTBY, OF WASHINGTON, DISTRICT OF COLUMBIA, ASSIGNOR TO THE STONE STRAW COMPANY, OF WASHINGTON, DISTRICT OF COLUMBIA, A CORPORATION OF NEW JERSEY.

GLUE-POT.

1,224,764.

Specification of Letters Patent.

Patented May 1, 1917.

Application filed February 21, 1916. Serial No. 79,757.

To all whom it may concern:

Be it known that I, LEWIS C. MALTBY, a citizen of the United States, residing at Washington, in the District of Columbia, have invented certain new and useful Improvements in Glue-Pots, of which the following is a specification.

My invention relates to an improvement in glue pots of the type more particularly adapted for applying a quick-setting glue evenly or uniformly upon a rapidly moving strip.

The present invention has to do more particularly with a removable scraper shoe or wear-plate of special design and form, which bears at a point upon the periphery of the glue-wheel, its curvature being on an arc larger than that of the wheel, whereby to insure its efficiency and effectiveness in accomplishing its purpose.

In the accompanying drawings:—

Figure 1 is a plan view;

Fig. 2 is an enlarged longitudinal vertical section;

Fig. 3 is a vertical transverse section on the line 3—3 of Fig. 2, looking to the right or in the direction of the arrow;

Fig. 4 is a transverse sectional view through the hinged block;

Fig. 5 is a bottom plan view of the latter; and

Fig. 6 is a perspective view of the removable scraper shoe or wear-plate.

A, is the glue-pot, and 1 is a transverse shaft journaled in bearings 2, 2, in the sides thereof, which will be hereinafter termed the glue-wheel shaft, and upon which the glue-wheel 3 is guided, the latter being located down well in the bed, so that the major portion of it is submerged in the glue. The glue-wheel shaft 1 is driven in any convenient manner by a belt, gear, or other mechanism not shown.

The scraper 4 is removably secured to a hinged support 5, and the latter is connected by a spring-hinge 6 to a bracket 7 held by bolts 8, 8, to the back of the glue-pot, as shown in Figs. 2 and 3, the spring hinge acting to normally swing the support 5 with its scraper upwardly away from the glue-wheel 3. As a simple means of adjusting the support 5 with its wear-plate with respect to the glue-wheel 3, a bolt 10 is pivoted to the pillar 10' by means of a pin 10^a, whereby the bolt may be swung laterally in and out of the slot 5' in the side

of the support (as shown in Fig. 1) and a wing-nut 9 on the bolt 10 is turned to regulate the adjustment. By loosening the wing-nut and swinging the bolt out through the slot 5', the support is released and may be swung up out of the way. It is returned to position by pressing it down, and swinging the bolt into the slot, and turning the wing-nut to obtain the desired adjustment of the scraper-shoe or wear-plate, herein-after described, to the periphery of the wheel 3.

The scraper 4 is provided with dowel pins 11, 11, which extend through holes 70 adapted to receive them in the support 5, and the scraper is secured rigidly in place by bolts 12, 12, as shown in Fig. 4.

The forward edge of the scraper 4 has a notch 13 corresponding in width to the thickness of the glue-wheel 3, it being adapted to straddle the latter and scrape the edges of the wheel, removing a superfluous glue adhering thereto.

The scraper-shoe or wear-plate 14, shown in Fig. 6, is removably inserted from above in the recess 13, its widened portion 15 fitting a corresponding recess, whereby it is held securely therein by friction, the support 5 above which the scraper 4 is bolted holding it in place. The forward face or surface 16 of this scraper-shoe or wear-plate, as shown in Fig. 2, is curved in an arc greater than the periphery of the glue-wheel 3, so that instead of fitting the latter, it touches it at a single point, or, more accurately speaking, line extending there-across.

The purpose of this construction is to provide space beneath this point or line of contact to facilitate holding back of superfluous glue carried along the periphery of the glue-wheel 3, which in this manner is brushed back much more effectively than in any other way, and more effectively than it would be if the two surfaces corresponded in curvature and precisely fitted each other.

In fact, when the face or surface 16 of the scraper-shoe or wear-plate becomes worn to the point where it does fit the periphery, it is then removed and replaced by a new one; but by constructing it in this way, it is possible by an occasional adjustment of the nut 9 on the upper end of the pillar 10 to prolong the life or efficiency of the scraper-shoe or wear-plate by throwing the contact farther and farther toward the upper angle

of the shoe or wear-plate, still getting the clearance or space below the point or line of contact with the periphery of the glue-wheel until finally the curvatures have become equal, when the scraper-shoe or wear-plate is removed and replaced, as previously explained.

In this manner, an excess or lack of uniformity of the glue as applied to the strip 10 traveling in contact with the upper edge of the glue-wheel is prevented.

The paper strips to form the tube, which this glue-pot is designed to coat, are drawn through two grooves in the plate 17, a tension-device 18 applying the required tension to these strips through the adjustment of the thumb-screws 19. These tension-devices are mounted on an arbor 20, which is removably secured to the post 21 by means 20 of the set-screw 22. The tension-devices can thus be removed with the arbor 20 at any time by unscrewing the set-screw 22.

It might be desirable to apply glue to two or even more of the strips which are spun 25 into the tube or straw, and this may be done by adding more glue-wheels or using a wider glue-wheel to accommodate two or even more strips. In that event, there would, of course, be as many grooves in the plate 17 as there 30 are strips being spun into the straw. Two only are shown, but it is evident that more might be employed.

I claim:

1. The combination with a rotatable wheel, 35 of a scraper-shoe or wear-plate having a curved face which coacts with the peripheral surface of the wheel, said contacting surfaces having the same general but non-concentric curves.

40 2. The combination with a rotatable wheel, of a scraper having a notched edge which straddles and substantially fits the sides of the wheel, and a wear-plate adjacent to the wheel having a curved face adapted to co-45 act with the peripheral surfaces of the wheel, and the curvature of which is non-concentric therewith.

3. The combination with a glue-pot and a glue-wheel rotatably mounted therein, of a 50 support mounted on the glue-pot, a spring hinge for pivotally connecting said support thereto, a scraper carried by the support, means for securing it thereto, and a wear-plate removably secured to the scraper.

55 4. The combination with a glue-pot and a glue-wheel rotatably mounted therein, of a scraper-shoe or wear-plate adapted to be held in position to coöperate with the periphery of the glue-wheel to remove superfluous glue therefrom, the operative surface of said shoe or wear-plate curved in an arc 60 greater than that of the periphery of the glue-wheel.

5. The combination with a glue-pot and a glue-wheel rotatably mounted therein, of a 65 scraper-shoe or wear-plate adapted to be held in position to coöperate with the periphery of the glue-wheel to remove superfluous glue therefrom, the operative surface of said shoe or wear-plate curved in an arc 70 greater than that of the periphery of the glue-wheel, and an adjustable support for said scraper-shoe or wear-plate.

6. The combination with a glue-pot and a glue-wheel rotatably mounted therein, of a 75 scraper-shoe or wear-plate adapted to be held in position to coöperate with the periphery of the glue-wheel to remove superfluous glue therefrom, the operative surface of said shoe or wear-plate curved in an arc 80 greater than that of the periphery of the glue-wheel, and a hinged spring-actuated support to which said scraper-shoe or wear-plate is detachably connected, and means for adjusting said support to regulate the position of the scraper-shoe or wear-plate with respect to the periphery of the wheel. 85

7. The combination with a glue-pot and a glue-wheel rotatably mounted therein, of a support mounted on the glue-pot, a scraper 90 detachably connected therewith, said scraper having a notched edge which straddles the wheel, and the sides of which scrape the sides of the wheel, and a scraper-shoe or wear-plate removably secured in said notch, 95 the forward face of which is curved, the curvatures of the said face and periphery of the glue-wheel being non-concentric.

8. The combination with a glue-pot, of a glue-wheel rotatably supported therein, a 100 support mounted on the pot, a spring hinge for connecting said support to the pot, the tension of which tends to swing the support away from the latter, and means for resisting the pressure of the spring and adjusting 105 the support with the scraper to the required position with respect to the periphery of the wheel.

9. The combination with a glue-pot, of a support connected therewith, a post carried 110 by the support, an arbor removably secured to the post, and tension-devices carried by the arbor for exerting a yielding pressure upon the support, and between which parts the object to be glued is passed. 115

10. The combination with a glue-pot, of a support connected therewith, a post carried by the support, an arbor removably secured to the post, and tension-devices carried by the arbor for exerting a yielding pressure 120 upon the support, and between which parts the object to be glued is passed, and means for regulating the amount of tension of said tension device.

In testimony whereof I affix my signature. 125
LEWIS C. MALTBY.
